UNITED STATES PATENT OFFICE.

CHARLES LICHTERMAN, OF PITTSSTON, PENNSYLVANIA.

WASHING MACHINE.

Application filed January 22, 1927. Serial No. 162,793.

The present invention relates to washing machines of the type comprising a tub arranged for oscillatory movement about a vertical axis.

5 Washing machines of this type are old and well known in the art, and are ordinarily provided with means within the tub for agitating the washing fluid and articles to be washed. The agitating means is usually 10 either (1) movable independently of the tub, such as an independently actuated dolly arranged on the bottom of the tub or slightly thereabove, or (2) fixedly secured to the tub for movement therewith, such as a plurality of vanes disposed on the bottom and side walls of the tub.

15 The present invention relates to a washing machine having a tub oscillatable about a vertical axis and having therein the second type of agitator mentioned above, namely, a plurality of agitating elements, such as vanes, fixedly secured to the tub and movable therewith.

20 In washing machines of this type, it is desirable to create a steady and powerful current which will continuously pass through and around the articles to be washed and thoroughly agitate the same. This should be accomplished without loss of power or 25 effectiveness of the circulating fluid, such as results from useless splashing which only means a loss of fluid washing power, and, in many instances, a waste of the fluid. This is a particular objection to such washing 30 machines as have heretofore been used of the type having a plurality of agitating vanes fixedly secured to the interior of the tub.

35 It has apparently been thought that a relatively large number of vanes arranged over an extended area within the tub is necessary in order to obtain the desired circulation of the washing fluid and agitation of the clothes. For this purpose, machines 40 of this type have been provided with vanes disposed substantially radially on the bottom of the tub and also vertically disposed on the side walls of the tub.

45 Use of washing machines with such an arrangement of vanes I have found results, due to extreme splashing, in a very considerable loss of washing fluid and also in a loss of washing power, since such fluid as is thrown upwardly or splashed is not part of

a current properly directed through the 55 clothes, or into the same, which is necessary in order to obtain the proper washing action.

An object of the present invention is, therefore, to provide an arrangement of fluid agitating vanes within the tub which 60 will create the necessary and desirable circulation of the washing fluid without splashing or waste of fluid power.

65 Other objects of the invention have to do with the provision of a tub construction, in a machine of the type wherein the tub oscillates about a vertical axis, which may be conveniently operated without annoyance because of splashing and will, at the same time, quickly and efficiently perform the 70 washing operation.

75 Still further objects of the invention have to do with simplicity of structure, efficiency and economy of operation, and will become clearer as the description proceeds in connection with the preferred embodiment of the invention disclosed in the accompanying drawings, wherein:

80 Figure 1 is a vertical sectional view on the line 1-1 of Figure 2.

85 Figure 2 is a horizontal sectional view with the tub or clothes container removed from the casing.

Figure 3 is a horizontal section through the tub or clothes container on the line 3-3 of Figure 1.

90 Referring to the drawings for a more detailed description, 10 indicates a casing, in the present instance, of substantially circular design, having a plurality of supporting legs 10'.

95 The casing contains therein suitable operating mechanism for imparting an oscillatory motion to a tub and clothes container 11, which will be described in detail after reference is first had to the preferred form 100 of operating mechanism illustrated in the drawings but to which no claim is made in this particular application.

105 The operating mechanism is supported upon a pair of transversely extending strips 12, 12', connected to the casing by means of angle brackets 13. A motor 14 is secured to the strip 12 and drives a pulley 15, which through a belt 16, operates a second pulley 105 17 upon a horizontal shaft 18. The shaft 18 is supported in bearings 19, and carries a worm 20, which meshes with a worm gear

21 upon a vertical stub shaft 22 having bearings in the strips 12, 12'.

22 The upper end of the shaft 22 carries a crank arm 23, which is pivotally connected 6 to a rack 24 by means of a wrist pin 25. The rack 24 is held in mesh with a rack gear or pinion 26 by means of a guide pin 27 upon a plate 28, which freely surrounds a vertical tubular shaft 29, secured to the tub 11, so 10 that the guide plate may move freely around the shaft 29 as an axis during operation of the rack 24. A gear 26 is connected with a tub supporting disk or platform 30, having an annular tub supporting portion 31 provided 15 with a surface of frictional material 32 such as rubber, cork or other suitable material.

23 As will be understood, operation of the rack and pinion from the motor 14 through 20 the driving connections described will result in an oscillatory movement of the pinion 26 and its tub supporting platform 30 about the tubular shaft 29, which serves as an axis or bearing for the gear and platform, the 25 shaft 29 being rotatable at its lower end in a tubular bracket 34 supported upon the platform strip 12. The lower end of the shaft 29 may be closed by a plug 35 and it is provided with a lateral opening 36 communicating 30 with a drain pipe 37, the shaft 29 thus serving as a portion of a passage for the discharge of washing fluid from the tub.

26 The tub 11 has substantially imperforate side walls 11' and a bottom wall 11'' which 35 is imperforate except for a centrally disposed drain opening 38 which communicates with the hollow shaft 39 secured to the tub. The opening 38 is formed in an annular up-standing valve seat member 39, having an 40 outwardly extending flange 40 and a plurality of radially disposed openings 41. These openings lead from the opening 38 into an annular chamber 42 which is arranged at the lower end of a tubular valve stem guide 45 43. A valve 44 has a vertically disposed stem 45 traversing the tubular guide member 43, and the valve handle 46 is disposed above the upper end of the tubular guide, whereby the valve 44 may be conveniently 50 raised and lowered to open and close the drain opening 38.

27 At its lower end the tubular guide 43 is provided with a plurality of openings 43' to permit fluid from the tub to flow through 55 the discharge opening 38 when the valve is raised. The latter may be maintained in raised position by any suitable means such as a detent pin 49 upon the stem, the pin being adapted to rest upon the top wall 43'' 60 of the guide 43 when the pin is drawn upwardly through an opening 50 (Fig. 3) therein and the valve stem is partially turned to carry the pin out of alignment with the reduced portion 50' of the opening.

65 The clothes container or tub is adapted

normally to rest within the casing 10 upon the platform 30, and when the latter is oscillated, the tub will have the same movement imparted thereto. In order to obtain a thorough circulation of the washing fluid, 70 the tub has arranged on its bottom, a plurality of vanes 52, which are disposed radially and are spaced inwardly from the side walls 11' of the tub. This arrangement of the vanes is of particular importance in a wash- 75 ing machine of this type, wherein the tub is oscillated about a vertical axis, for the reason that by providing a free or unobstructed space between the outer ends of the vanes and the tub side wall 11, instead of arranging, for instance, vertically disposed vanes 80 on the inner side wall of the tub, objectionable splashing of the washing fluid is avoided, and, furthermore, instead of a splashing 85 action there is obtained a steady and powerful circulation of the fluid of the character described below.

28 When the tub is substantially filled with clothes and the fluid level is at substantially the line 3-3 (Fig. 1), operation of the tub 90 will not cause a splashing of the fluid, but instead, the agitating vanes 52 will cause the fluid adjacent the bottom to flow outwardly to the side wall of the tub where it is directed upwardly, as indicated by the 95 arrows in Figure 1, and then inwardly and downwardly. The inwardly flowing currents, indicated generally by the arrows in Figure 3, tend to converge toward a point 100 disposed between the inner ends of the vanes and substantially equi-distantly therebetween. These inwardly flowing currents have a very considerable force, but do not splash or foam to any substantial extent. The result is that the entire fluid power is 105 directed in steady streams or currents continuously flowing upwardly toward the top of the tub, then inwardly toward the center, and then downwardly at substantially the center of the tub toward the vanes. The 110 articles being washed will be carried, to a certain extent, by these currents, which will pass around and through the articles and thereby effect a thorough washing operation. 115

29 A particular feature of this invention is 115 the provision of a tub having above the tops of the baffles and adjacent the side walls, an unobstructed area. That is to say, the side walls above the tops of the baffles are substantially plane, or, in other words, are 120 not provided with vanes or baffles which would destroy, or, at least deflect substantially, the course of the inwardly flowing currents. It is preferable, as explained, that the baffles be located so as to leave between 125 the side walls and the ends of the baffles, a space for the passage of fluid, since the inwardly flowing currents are stronger and more effective with this construction, and it 130 is desirable that the side walls above the

tops of the baffles be formed so as not to obstruct the horizontal flow of fluid along the face of the walls.

For the purpose of increasing the power of the stream and the baffle action of the vanes, they are preferably formed, as shown in the drawings, with their upper edges 52' directed upwardly toward their outer ends and their outer end edges 52'' are curved downwardly and inwardly. This formation gives the vanes a greater height at their outer ends 52'' than at their inner ends, which is desirable in view of the upwardly directed currents which are formed at the outer ends. The vanes or baffles, in the present instance, are formed separately from the tub and are secured thereto by means of laterally extending lugs 53'.

Although there is no considerable splashing action caused by the vanes, the tub may be provided with a cover 54 and the casing has a cover 55 which results in a construction in which the clothes container is entirely enclosed.

When it is desirable to interrupt the operation of the clothes container, it may be lifted from the platform 30 by any suitable mechanism such as the rock shaft 56 having a cam 57 arranged below the shaft 29. The shaft 56 may rock to bring the cam into engagement with and to raise the shaft 29 and the tub, as by means of a crank arm 57 on the rock shaft connected with a pitman 58 extending upwardly to a crank 59 mounted on a short shaft 60 carried by a hand operable lever 61. It will be understood that by simply operating the lever 61, the rock shaft 56 and cam 57 may be actuated to raise the shaft 29 and thus lift the tub from the oscillating platform 30 upon which it rests. The tub may thus be raised without interrupting the movement of the platform and when the tub is lowered upon the platform, its oscillating motion will be resumed.

A narrow wear strip 62 is made secure to the bottom of the tub so as to be interposed between the strip of friction material 32 on the operating platform and the bottom of the tub, and thus, wear upon the material forming the bottom of the tub is eliminated.

If desired, the washing action of the currents formed by the vanes 52 during oscillation of the tub may be augmented by interiorly corrugating the wall of the tub as at 63. These corrugations may be spaced apart as illustrated in the drawings, or may be extended entirely around the tub side walls, if desired. It will be understood, however, that such corrugations do not affect the currents or streams created by the vanes and simply have a frictional action upon the clothes.

By the term "vanes" as used throughout the specification and claims, is meant any fluid obstructing wall or baffle, irrespective

of its cross-sectional dimensions, which has substantially the effects described, whether formed integrally with the tub, or independently of the tub and secured thereto, as shown in the drawings.

Obviously, the invention is not limited to the details of construction illustrated and described, and such modifications may be made therein as come within the following claims:

I claim:

1. A washing machine comprising a tub adapted to contain clothes and washing fluid, means for oscillating said tub about a substantially vertical axis and a plurality of agitating vanes fixedly positioned on the bottom of the tub, said vanes being spaced inwardly from the side walls of the tub whereby to provide an unobstructed space between the outer ends of the vanes and the side walls of the tub for free circulation of washing fluid.

2. A washing machine comprising a tub adapted to contain clothes and washing fluid, means for oscillating said tub about a substantially vertical axis disposed substantially at the center thereof and a plurality of substantially radially disposed agitating vanes fixedly positioned on the bottom of the tub, said vanes being spaced inwardly from the side walls of the tub whereby to provide an unobstructed space between the outer ends of the vanes and the side walls of the tub for free circulation of washing fluid.

3. A washing machine comprising a tub adapted to contain clothes and washing fluid, means for oscillating said tub about a substantially vertical axis and a plurality of substantially radially disposed fluid-agitating vanes fixedly positioned on the bottom of the tub, said vanes being spaced inwardly from the side walls of the tub, whereby to provide an unobstructed space between the outer ends of the vanes and the side walls of the tub for free circulation of washing fluid, and spaced radially outwardly from the center of the tub.

4. A washing machine comprising a tub adapted to contain clothes and washing fluid, means for oscillating said tub about a substantially vertical axis and a plurality of substantially radially disposed fluid-agitating vanes having upwardly inclined outer ends fixedly positioned on the bottom of the tub, said vanes being spaced inwardly from the side walls of the tub whereby to provide an unobstructed space between the outer ends of the vanes and the side walls of the tub for free circulation of washing fluid.

5. A washing machine comprising a tub adapted to contain clothes and washing fluid, means for oscillating said tub about a substantially vertical axis and a plurality

- of substantially radially disposed fluid-agitating vanes having upwardly inclined outer ends fixedly positioned on the bottom of the tub, said vanes being spaced inwardly from the side walls of the tub, whereby to provide an unobstructed space between the outer ends of the vanes and the side walls of the tub for free circulation of washing fluid, and spaced radially outwardly from the center of the tub.
6. A washing machine comprising a tub adapted to contain clothes and washing fluid, means for oscillating said tub about a substantially vertical axis disposed in substantially its center and a plurality of relatively flat, upstanding and substantially radially disposed fluid-agitating vanes fixedly positioned on the bottom of said tub, said vanes being spaced substantially equidistantly about said axis and spaced outwardly therefrom and radially inwardly from the side walls of the tub, the space between the outer ends of said vanes and the side walls of the tub being unobstructed to permit free circulation of washing fluid.
7. A washing machine comprising a tub adapted to contain clothes and washing fluid, means for oscillating said tub about a substantially vertical axis disposed at substantially its center and a plurality of relatively flat, upstanding and substantially radially disposed fluid-agitating vanes fixedly positioned on the bottom of said tub, said vanes being spaced substantially equidistantly about said axis and spaced outwardly therefrom and radially inwardly from the side walls of the tub, the space between the outer ends of said vanes and the side walls of the tub being unobstructed to permit free circulation of washing fluid, the upper edges of said vanes being inclined upwardly and outwardly whereby the vanes extend upwardly a more substantial distance at their outer ends than at their inner ends.
8. A washing machine comprising a tub adapted to contain clothes and washing fluid, means for oscillating said tub about a substantially vertical axis disposed substantially at the center thereof, and a plurality of substantially radially disposed agitating vanes fixedly positioned on the bottom of the tub, the side walls of the tub above the tops of the vanes being substantially devoid of obstructions to the flow of liquid horizontally along the walls and said vanes being spaced inwardly from the side walls of the tub whereby to provide an unobstructed space between the outer ends of the vanes and the side walls of the tub for free circulation of washing fluid.
9. A washing machine comprising a tub adapted to contain clothes and washing fluid, means for oscillating said tub about a substantially vertical axis, and a plurality of substantially radially disposed fluid-agitating vanes fixedly positioned on the bottom of the tub above the tops of the vanes being substantially devoid of obstructions to the flow of liquid horizontally along the walls, and said vanes being spaced inwardly from the side walls of the tub whereby to provide an unobstructed space between the outer ends of the vanes and the side walls of the tub for free circulation of washing fluid, and spaced radially outwardly from the center of the tub.
10. A washing machine comprising a tub adapted to contain clothes and washing fluid, means for oscillating said tub about a substantially vertical axis disposed substantially at the center thereof, and a plurality of substantially radially disposed agitating vanes fixedly positioned on the bottom of the tub, the side walls of the tub above the tops of the vanes being substantially devoid of obstructions to the flow of liquid horizontally along the walls, and said vanes being spaced inwardly from the side walls of the tub whereby to provide an unobstructed space between the outer ends of the vanes and the side walls of the tub for free circulation of washing fluid and being spaced outwardly from the center of the tub, and an upstanding post occupying the space at the inner ends of said vanes adapted to engage and deflect currents flowing radially inwardly from the side walls thereof.
11. A washing machine comprising a tub adapted to contain clothes and washing fluid, means for oscillating said tub about a substantially vertical axis, and a plurality of substantially radially disposed fluid agitating vanes having upwardly inclined outer ends fixedly positioned on the bottom of the tub, said vanes being spaced inwardly from the side walls of the tub, whereby to provide an unobstructed space between the outer ends of the vanes and the side walls of the tub for free circulation of washing fluid, and spaced radially outwardly from the center of the tub, and an upstanding post occupying the space at the inner ends of said baffles to obstruct and deflect currents flowing radially inwardly from the side walls.
12. A washing machine comprising a tub adapted to contain clothes and washing fluid, means for oscillating said tub about a substantially vertical axis, and a plurality of substantially radially disposed fluid-agitating vanes fixedly positioned on the bottom of the tub, the side walls of the tub above the tops of the vanes being substantially devoid of obstructions to the flow of liquid horizontally along the walls, and said vanes being spaced inwardly from the side walls of the tub whereby to provide an unobstructed space between the outer ends of the vanes and the side walls of the tub for

free circulation of washing fluid, and spaced radially outwardly from the center of the tub, and an upstanding post occupying the space at the inner ends of said vanes to obstruct and deflect current flowing radially inwardly from the side walls thereof.

13. A washing machine comprising a substantially vertically disposed cylindrical tub having a substantially uninterrupted inner periphery, and oscillatable about a substantially vertical axis, power driven means for oscillating the tub about said vertical axis, an axially disposed post projecting upwardly for a substantial distance from the bottom of the tub, and liquid deflecting means operative to deflect the liquid in the tub outwardly and upwardly during oscillation thereof, said deflecting means being rigid

with and on the bottom of said tub, and being spaced from the inner periphery 20 thereof.

14. A washing machine comprising a substantially vertically disposed cylindrical tub having a substantially uninterrupted inner periphery and oscillatable about a substantially vertical axis, power driven means to oscillate the tub about said axis, and liquid deflecting means to deflect the liquid in the tub outwardly and upwardly during oscillation thereof, said deflecting means being 25 rigid with and on the bottom of the tub, and being spaced from the inner periphery thereof.

In testimony whereof I have hereunto set my hand.

CHARLES LICHTERMAN.
